ATTORNEY

UNITED STATES PATENT OFFICE

137,621

DESIGN FOR A UNIFORM OR SIMILAR ARTICLE

William D. Kellar, Newton, Mass.

Application February 9, 1944, Serial No. 112,525

Term of patent 7 years

(Cl. D3—26)

To all whom it may concern:

Be it known that I, William D. Kellar, a citizen of the United States of America, residing in Newton, county of Middlesex, and State of Massachusetts, have invented a new, original, and ornamental Design for a Uniform or Similar Article, of which the following is a specification, reference being had to the accompanying drawing, forming part thereof, wherein,

Figure 1 is a front view of a uniform or similar article showing my new design, and

I claim:

The ornamental design for a uniform or similar article, substantially as shown.

WILLIAM D. KELLAR.
